EDWARD KIRBY BOTTLE, OF ELMIRA, NEW YORK, ASSIGNOR TO AMERICAN SALES BOOK COMPANY, LIMITED, OF TORONTO, ONTARIO, CANADA, A CORPORATION OF ONTARIO, CANADA

MANIFOLDING SALES BOOK

Application filed May 23, 1922. Serial No. 562,959.

This invention relates to manifolding devices and with respect to its more specific features to manifolding books, pads and the like and elements thereof.

5 One of the objects of the invention is the provision of a simple and practical manifolding unit adapted to be utilized in various types of manifolding books and the like.

Another object of the invention is the 10 provision of an efficient and convenient manifolding book or pad adapted for making five or more records at one writing.

Other objects will be in part obvious and in part pointed out hereinafter.

15 The invention accordingly consists in the features of construction, combinations of elements and arrangements of parts which will be exemplified in the construction herein-after set forth, and the scope of the application of which will be indicated in the following claim.

In the accompanying drawings forming part of the specification and wherein similar reference characters refer to similar parts 25 throughout the several views;

Figure 1 is an edge view of a folded record sheet with a supplemental pasted leaf;

Fig. 2 is a perspective view of a manifolding book, or pad, including a plurality of 30 the record sheets of Fig. 1; and

Fig. 3 is a perspective view of the book of Fig. 2, associated with a supplemental pad of tissue leaves.

Referring now more specifically to the 25 drawings and particularly to Fig. 1 thereof, there is illustrated a folded record sheet composed of the integrally connected record leaves 1, 2, and 3, the numeral 1 indicating the original leaf on which the original inscription is made, the numeral 2 indicating the duplicate and 3 the triplicate to which the inscription is to be transferred. The leaves 1, 2, and 3 may be made from a single paper strip, or sheet, and may be folded 40 along the two parallel lines 5 and 6 into superposed relation, that is, with its parts superposed one upon another the end record leaf 2 lying between the leaves 1 and 3, the underlying leaf 3 having an extension or stub 45 7 for binding purposes and having a weak-

ened line 8 (see Fig. 1) for facilitating the tearing of the leaf 3 from the stub 7.

The numeral 9 indicates a supplemental record sheet pasted to the first mentioned record sheet. As illustrated the supplemental record sheet is pasted to the under face of the topmost leaf 1, the paste line being generally parallel to the folding lines as indicated at 10 and being adjacent the fold line 6. The longitudinal dimension of the supplemental record sheet is such that it may lie in superposed relation to the three leaves 1, 2, and 3 and extend across the fold line 5 between the topmost leaf and the leaf 3, which latter is next adjacent the topmost leaf when enumerating from the free end of the record sheet in the direction of the bound end of the leaf 3. The supplemental record sheet 9 is folded along the line 11 parallel to the folds in the other sheet and is thus divided into supplemental sheet sections or leaves 12 and 13.

In Fig. 2 the manifolding unit illustrated in Fig. 1 is shown assembled with other similar manifolding units in a pad or book, the 75 stub ends of the several sets of units being bound together by the staples 14 which may be extended through a suitable backing 15 of pasteboard, manila paper or the like. The numeral 16 indicates a transfer leaf bound 80 with the pad by the staples 14 and working from the stub end of the pad into and out of position between the supplemental leaf 13 and the leaf 3, the transfer leaf 16 being coated on both faces with carbon in order to transfer impression direct to the leaf 3 and in reverse to the underlying face of the leaf 13. The numeral 17 indicates a second transfer leaf bound next adjacent the transfer leaf 16 by the staples 14 and also working from the 85 bound end of the record sheets into superposed relation with the record leaves. The transfer leaf 17 extends across the fold line 5 between the topmost record leaf 1 and the bound record leaf 3 and is folded at 18 parallel to the folds 5 and 11. It will be understood that the record sheets, whether the opaque record sheet of leaves 1, 2, and 3 or the sheet of transparent record leaves 12 and 13, are perforated or weakened along the fold 90 100

lines for the purpose of efficient and convenient tearing apart thereof.

In Fig. 3 the book illustrated in Fig. 2 is shown assembled with a second pad of transparent leaves, as tissue leaves 20, one of the leaves 20 being shown in manifolding position relative to the other leaves. This second pad is stapled to a support leaf 21 of pasteboard or metal which is hinged to the backing 15, as by means of a flexible connection 22, on an axis parallel to the fold lines of the record leaves, the support leaf 21 being extended as at 23 beyond the bound end of the pad 1 for positioning the second pad of transparent leaves 20. If desired, the pad of leaves 20, instead of working from the bound end of the pad 1, might be attached to the support 21 at the side of the pad 1 (not shown).

In Figs. 2 and 3 the book composed of the units illustrated in Fig. 1 is shown with the various record leaves and transfer leaves in relative position for manifolding, it being understood that the various leaves will be flattened out before inscription is made. In Fig. 2, a record made upon the original leaf 1 will be transferred direct to the opaque leaves 2 and 3 and in reverse to the tissue leaves 12 and 13 of the supplemental sheet

9. Also the supplemental leaf 13 will receive a direct impression through the transfer leaf, or sheet 17.

In Fig. 3, in addition to the recording effect, as described in connection with Fig. 2, the transparent leaf 20 of the second pad will receive a reverse impression of the record. By the construction illustrated in Fig. 2 five copies are made at one writing, whereas six are made by the construction illustrated in Fig. 3.

Thus by the above described construction are accomplished, among others, the objects hereinbefore referred to.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claim is intended to cover all of the generic and specific features of the invention herein described, and all statements of the scope of the invention which, as a matter of language, might be said to fall therebetween.

Having described my invention, what I claim as new and desire to secure by Letters Patent is:

In a manifolding pad, in combination, a plurality of relatively superposed sets of record leaves and transfer material, each of said

sets including a record sheet folded on two lines parallel to the bound end of the pad to provide three superposed record leaves, the end record leaf lying between the other two record leaves, and a supplemental record sheet pasted to the under face of the topmost of said three leaves on a line parallel to the folding lines of the other sheet, lying in superposed relation to said three leaves, and extending across the fold line between said topmost leaf and the leaf next adjacent thereto in the direction of the bound end of the first mentioned record sheet so as to provide two additional record leaves, said transfer material including two relatively superposed transfer leaves supported in a position to work from the bound end of the first mentioned record sheets into superposed relation with said record leaves, one of said transfer leaves extending across the fold line between the topmost record leaf and the bound record leaf, said supplemental record sheet being transparent, a backing for said pad, a support leaf hinged to said backing and a second pad held on said backing, the leaves of said second pad being transparent and adapted to be superposed relative to the leaves of the other pad.

In testimony whereof I affix my signature.

EDWARD KIRBY BOTTLE.
